ELECTRIC COOKER AND SERVER COMBINATION

Thomas Chinn and Paulyne Joe, Sacramento, Calif.

Application January 7, 1958, Serial No. 49,159

Term of patent 14 years

(Cl. D81—17)

FIG. 1

FIG. 2

FIG. 3

FIG. 4

Fig. 1 is a top plan view of an electric cooker and server combination, showing our new design;

Fig. 2 is a side elevational view thereof taken from the right of Fig. 1;

Fig. 3 is a side elevational view taken at a 90° angle from Fig. 2, and;

Fig. 4 is a bottom plan view thereof.

We claim:

The ornamental design for an electric cooker and server combination, as shown.
